UNITED STATES PATENT OFFICE.

HERBERT E. WHITE, OF YOUNGSTOWN, OHIO, ASSIGNOR TO THE GENERAL FIREPROOFING COMPANY, OF YOUNGSTOWN, OHIO, A CORPORATION OF OHIO.

RIBBED-SHEET-METAL-EXPANDING MACHINE.

1,125,786.

Specification of Letters Patent.

Patented Jan. 19, 1915.

Application filed March 13, 1912. Serial No. 683,570.

To all whom it may concern:

Be it known that I, HERBERT E. WHITE, a citizen of the United States, residing at Youngstown, in the county of Mahoning and State of Ohio, have invented certain new and useful Improvements in Ribbed-Sheet-Metal-Expanding Machine, of which the following is a specification.

This invention relates to the general subject of machines for preparing and forming sheet metal products, and more particularly to the production of ribbed sheet metal structures possessing special utility as a metal lath, or as a centering form in connection with reinforced concrete for building and other purposes.

To this end, the invention contemplates a simple and practical construction of sheet metal expanding machine having special advantages in performing its part of the process of developing and producing that type of expanded sheet metal product known on the market as the ribbed diamond lath. In this connection, the invention embodies means for expanding ribbed metal sheets in a rapid and economical manner, after such sheets have been preliminarily stiffened and grooved by means such as disclosed in my Patent No. 1,056,962, dated March 25, 1913, and preliminarily slit and upset by means such for instance as disclosed in Patent No. 1,049,632, granted Jan. 7, 1913.

A special object of the invention is to provide a machine whose function is to effect a rapid and uniform expanding action on the ribbed sheet metal blank, wherein the reticulated web portions between the ribs have been produced by longitudinally disposed slits or cuts disposed parallel to the ribs, and to accomplish the expanding action upon such sheet without placing undue or excessive strain on any part thereof. Also, a distinctive object of the invention, in this same connection, is to not only secure a rapid and uniform expansion of the reticulated web portions of the sheet, but also to strengthen the edges of the rib walls and safeguard the sheet from fracture along the line of cut contiguous to the edge of the ribs. In other words, the present invention includes means for producing what may be termed, a back-turned reinforce bead at the edges of the rib walls, the reverse turn or bend of these beads serving to throw

the edges thereof out of the line of cut, and hence obviating any tendency of the reticulated webs to tear away from the edge flanges of the ribs, when the sheet is expanded. These beads also serve to materially stiffen the ribs both laterally and vertically.

Another object of the invention of practical importance is that of the provision of means for straightening out, and correcting buckling in, the expanded reticulated web portions, when the expanding action has ceased.

With these and other objects in view which will readily appear to those familiar with the art, the same consists in the novel construction, combination and arrangement of parts hereinafter more fully described, illustrated and claimed.

A preferred embodiment of the invention is shown in the accompanying drawings, in which—

Figure 1 is a top plan view of an expanding machine embodying the present invention, the view indicating one of the feeding and expanding units that are repeated to any desired number according to the area of the expansion desired, said view also showing the provision of a pair of delivery rolls for giving final set to the expanded sheet. Fig. 2 is an elevation of the feeding end portion of the machine. Fig. 3 is a front end view of the machine. Fig. 4 is a sectional view of the stationary expanding guide constituting the intermediate member of each feeding and expanding unit of the machine. Fig. 5 is a sectional view of one of the feeding and expanding units on the line 5—5 of Fig. 1. Fig. 6 is an enlarged detail sectional view of a section of one pair of feed rolls, having the die elements for giving form and set to the reinforce edge beads at the edges of the rib walls. Fig. 7 is an enlarged detail view showing a pair of the guiding members of the stationary expanding guide, the view also indicating the feature of the pass between the upper and lower members of the guide being slightly above the level of what may be termed the pass between the upper and lower feed rolls. Fig. 8 is an enlarged sectional view of a section of the combined delivery and setting rolls on the line of section 8—8 of Fig. 1. Fig. 9 is a sectional view and Fig. 10 is a plan view of an ex-

panded reticulated sheet metal blank in the form given to it by passing through the expanding machine claimed herein. Fig. 11 is a plan view of a ribbed and slitted blank 5 in the form in which it is fed to the improved expanding machine. Fig. 12 is a detail sectional view of a fragment of the ribbed and slitted sheet on the line 12—12 of Fig. 11.

10 Like references designate corresponding parts in the several figures of the drawings.

The improved machine embodies in its organization a machine stand or frame designated in its entirety by the numeral 1, 15 and designed to have mounted therein any predetermined number of feeding and expanding units, according to the area of the expansion desired. These feeding and expanding units are similar in construction 20 and action, so a description of one of such units will suffice for the others. Referring particularly to the drawings, it will be observed that each feeding and expanding unit comprises and includes opposite pairs of 25 feed rolls suitably mounted on the machine stand or frame and driven by suitable gearing, and a stationary expanding guide between said pairs of rolls. The pairs of feed rolls respectively act as feeders for the 30 expanding guide in advance thereof, and as delivery or drawing means for the expanding guide in rear thereof, but considering this combination as one working unit of the machine, which is repeated in any 35 desired number, it will be observed particularly from Fig. 5 of the drawings that each pair of feed rolls consists of upper and lower rolls 2 and 3, respectively, which are arranged in superposed relation, and are provided with a series of regularly spaced annular feeding collars 4 and 5, respectively, and which collars correspond in number and spacing to the ribs of the sheet metal blank 40 as will presently more fully appear.

45 A feature of practical importance in connection with the present invention is the die formation of the complementary collars 4 and 5. That is to say, the collars 5 of the lower roll 3, of each pair, are provided therein with the open peripheral approximately V-shaped grooves 6 to seat therein the ribs of the sheet metal blank, and at the outer edges of the groove walls in the collars 5, the latter are provided with the former-horns 7 having inclined outer faces and constituting fulcrum points lying opposite shaping grooves 8, which are provided in the collars 4 of the upper roll at the base and opposite sides of peripheral projecting 50 holding tongues 9, that extend into the seating grooves 6 of the complementary collars 5. In order to secure a positive die action by 60 means of the elements referred to, each of the collars 4 of the upper roll is also provided at the outer sides of the shaping

groove 8 with marginal angular die projections 10, overlying the outer inclined faces of the horns 7, as plainly appears in Fig. 6 of the drawings.

The stationary expanding guide between 70 the pairs of rolls referred to may be designated in its entirety by the letter G. The guide consists of a series of regularly spaced and paired upper and lower guide members 11 and 12, held in place by suitable supports 75 13 and 14. The lower member 12 of each pair of guide members is provided therein with a guiding groove 15 for a rib of the sheet metal blank, while the upper member 11 paired therewith is truncated as at 16 to provide a flat head overlying the horns of the member 12 and serving to maintain the form of the sheet metal blank, while at the same time offering a reduced frictional resistance to its passage through the guide. 80 From Figs. 6 and 7 of the drawings, it will be observed that the pass between the upper and lower members of the expanding guides is slightly raised above the plane or level 85 of the pass between the upper and lower feed rolls 2 and 3, with the result of causing the edge portions of the ribs of the sheet metal blank to closely hug the horns of the lower guide members 12, so that the set of 90 such edge portions is maintained.

The expanding effect on the metal blank is accomplished by having the paired members of the guide divergently arranged, and the collars of the opposite pairs of feed 95 rolls correspondingly spaced, as plainly 100 shown in Fig. 1 of the drawings.

At the end of the series of feeding and expanding units made up of the rolls 2 and 3, and the expanding guides G, there is 105 located a pair of combined delivery and setting rolls 17—18 arranged in superposed relation and having complementary collars 19 and 20 of substantially the same construction as the collars 4 and 5 of the feed rolls 2 and 3, in order to maintain the form and 110 give set to the bead formation at the edges of the rib walls adjoining the reticulated expanded web. In other words, the collars 20 of the delivery rolls are provided with the rib seating grooves 21, and former horns 22, while the collars 19 are provided with the peripheral holding tongues 23, shaping 115 grooves 24, at the bases of the tongues, and the marginal die projections 25, of the same character and bearing the same relation as the corresponding elements of the feed rolls. In addition to these elements, a distinctive 120 feature of the delivery rolls is that of providing the upper roll 17 with a plurality of depressing collars 26, alternating with the collars 19 and adapted to have a bearing-down engagement with the central portion of the reticulated expanded webs of the metal sheet for the purpose of straining 125 such expanded portions downward slightly 130

below their normal plane, so that when the said portions spring back they naturally resume a substantially flat plane with reference to the ribs of the metal sheet. This 5 provides definite means for straightening out, and correcting buckling-in, the expanded web portions of the sheet when the expanding action has ceased. Other delivery rolls of the same construction with straight 10 guides between them may be repeated beyond the first pair of rolls if so desired.

The metal sheet to be acted upon by this machine is in the form shown in Figs. 11 and 12 of the drawings, the same being provided with longitudinally extending ribs 27 and longitudinally slotted web portions 28 which have the arched form shown in Fig. 6 and indicated in Fig. 12. However, the ribbed and slotted sheet to be acted upon 15 by the expanding mechanism is provided at the edges of the rib walls with marginal flanges 29, which are disposed at substantially right angles to the longitudinal plane of the ribs 27. This design of metal sheet 20 is fed to the first set of the feed rolls 2 and 3 over a feeding table 30, at the feeding-in end of the machine. These first rolls 2 and 3 have the die action plainly shown in Fig. 6. This action consists in the bending- 25 down of the said marginal flanges 29 over the former horns 7, thus converting said flanges into back-turned reinforced beads at the margins or edges of the rib wall. The reverse turn or bend of these beads serves 30 to throw the edges thereof out of the line of strain incident to the expanding and straightening out of the slotted reticulated web portions 28 of the sheet metal blank, thereby obviating any tendency of such web 35 portions to tear away along the line of longitudinal cuts at the edge flanges of the ribs. These beads also serve to stiffen the ribs both laterally and vertically. Succeeding feed rolls maintain and give set to said marginal beads and the diverging guide members between the said rolls automatically 40 expand the sheet as it is fed through them.

I claim:

1. An expanding machine for ribbed sheet metal including an expanding device, and a feeding device, the latter having die elements comprising means for producing reinforce beads at the flanged edges of the rib walls.
2. An expanding machine for ribbed sheet metal including an expanding device, and a feeding device, the latter having die elements comprising means for producing back-turned reinforce beads at the flanged edges of the rib walls.
3. An expanding machine for ribbed sheet

metal including an expanding device, and a feeding device, the latter having die elements comprising means for producing reinforce beads with a reverse bend to throw 65 the edges out of the line of strain incident to the expanding action.

4. An expanding machine for ribbed sheet metal including a feeding and expanding unit consisting of opposite pairs of feed 70 rolls and a stationary expanding guide between said pairs of rolls and having diverging guide members, the said feed rolls having die elements for imparting a reverse bend to the marginal flanges of the rib walls. 75

5. An expanding machine for ribbed sheet metal including an expanding device, and upper and lower feed rolls, the lower feed roll having annular collars provided with peripheral groove and former horns at the 80 sides of the grooves, and the upper feed roll having annular collars provided with peripheral holding tongues, opposite shaping grooves at the bases of said tongues, and angular die projections at the outer margins of said shaping grooves. 85

6. An expanding machine for ribbed sheet metal including opposite pairs of feed rolls, and a stationary expanding die between said pairs of rolls, and having diverging upper and lower paired guide members, each lower guide member having a rib receiving and guiding groove, and each upper guide member having a truncated head overlying the horns of the lower member, and the passes between the upper and lower members of the guide lying in a horizontal plane that is higher than the horizontal plane of the passes between the feed rolls. 95

7. An expanding machine for ribbed sheet metal including an expanding device, a feeding device, and a device located beyond the expanding mechanism and having depressing means arranged to engage the expanded web portions of the sheet between each pair of ribs thereof. 105

8. An expanding machine for ribbed sheet metal including an expanding device, a feeding device, and a pair of delivery rolls located beyond the expanding mechanism and having passes corresponding to those of the expanding mechanism and also provided with depressing collars arranged to depress the expanded web portions below their normal plane. 110

In testimony whereof I hereunto affix my signature in the presence of two witnesses.
